(57) **CLAIM**

The ornamental design for a display screen or portion thereof with animated graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first image in a sequence for a display screen or portion thereof with an animated graphical user interface showing our new design; and FIG. 2 is a second image thereof.

FIG. 3 is a front view of an enlarged portion of FIG. 1 showing our new design; and, FIG. 4 is a front view of an enlarged portion of FIG. 2 showing my new design.

The appearance of the transitional image sequentially transitions between the images shown in FIGS. 1 and 2 or FIGS. 3 and 4. The process or period in which one image transitions to another image forms no part of the claimed design. The broken lines illustrating portions of the automobile and the display screen or the portion thereof form no part of the claimed design. The dot-dash broken lines defining boundaries of the claimed design form no part of the claimed design. The diagonal slanted solid lines illustrate crosscuts and are not part of the claimed design.
